S. S. De Mersay of New York No. 3.

Letter Patent No. 2499, Dated Oct. 31, 1866.

Design for a Beach Lamp.

The schedule referred to in this Letter Patent and making part of the same.

As all where it may concern:

Be it known that I, S. S. De Mersay of No. 2499, in the city, County and State of New York have invented a new and Improved Design for Beach Lamps, and do hereby declare that the following a full, clear and exact description thereof which will enable others skilled in the art to make and use the same, reference being had to the accompanying drawing forming part of this Specification in which,

Figure 1. represents a front elevation of this invention.

Figure 2. is a horizontal section of the same.

Similar letters of reference indicate like parts.

The principal features of this Design are the bevels on the circumference of the front plate which is set in a polygonal case; and the undulating glass occupying one of the sides of said case and placed opposite a series of reflecting surfaces formed in the interior of the lamp in such a manner that a lamp of elegant, simple character which, makes a good appearance during the day and gives a brilliant light at night.

A. represents the front plate of this lamp which is bevelled in the polygonal case B., and provided with a series of bevels at A., as clearly shown in Figure 1. of the drawing. — One side of the case is occupied by an undulating glass, or by a series of glasses, put together so as to form an undulating surface D., and the interior of the case forms a series of reflecting surfaces C., see Figure 2., which materially assist in increasing the effect and brilliancy of the lamp by day and night.

By these means a beach lamp is obtained of a novel and elegant appearance. Having thus described my invention claim as follows and describe by Letter Patent, — The Design for a beach lamp as shown and described.

W. G. F. / Mr. J. Mc. Murray. / A. S. De Mersay.
